(57) **CLAIM**

The ornamental design for a pumpkin support and decorating device, as shown and described.

DESCRIPTION

FIG. 1 is a top perspective view of the pumpkin support and decorating device of the present invention showing our new design;

FIG. 2 is a top plan view thereof;

FIG. 3 is a front elevational view thereof;

FIG. 4 is a side elevational view thereof; and,

FIG. 5 is rear elevational view thereof.

The broken line showing of the pumpkin support and decorating device in FIGS. 1-5 is for the purpose of illustrating only and forms no part of the claimed design.

All surfaces not shown form no part of the claimed design.

1 Claim, 3 Drawing Sheets
